UNITED STATES PATENT OFFICE.

WILLIAM GUY-PELL, OF LONDON, ENGLAND.

RETORT APPARATUS FOR THE TREATMENT OF MATERIALS SUCH AS SHALE, COAL, AND THE LIKE.

Application filed July 17, 1924. Serial No. 726,511.

To all whom it may concern:

Be it known that I, WILLIAM GUY-PELL, a subject of the King of Great Britain and Ireland, residing at London, England, have 5 invented Improvements in or Relating to Retort Apparatus for the Treatment of Materials such as Shale, Coal, and the like, of which the following is a specification.

This invention relates to apparatus for 10 the heat treatment of shale, coal and other carbonaceous or like materials.

In retorts where large masses of material are to be dealt with, the difficulty of heating the same at the centre is well recognized, especially when low temperature retorting conditions are to prevail, this being due to the inherent low heat conductivity of the materials. To overcome this, it has been proposed, in various ways, to more or 20 less subdivide the mass by means of walls of better heat conducting characteristics extending into the mass, thereby obtaining a more equable heating of the same.

In some cases these walls are constituted 25 by ribs forming an integral part of the retort, but the construction is an expensive one if such plurality of ribs is provided as is desirable to thoroughly subdivide the mass. Moreover this construction does not 30 readily permit of renewal of worn out parts being effected, while no provision is made for expansion or contraction.

According to the present invention, for 35 the purpose of subdividing the mass of material to be heated, there is provided a plurality of ducts, the distance between the walls of which is small in relation to the total cross sectional area of the ducts, the said ducts being contained in a single or 40 common heating zone through the whole length of which they extend and being free to expand and contract either individually or collectively.

The walls of the ducts may be of any 45 suitable shape, but may advantageously be constituted by tubes of circular cross section which are preferred on the score of cost of manufacture.

Apparatus according to the invention is 50 illustrated in the accompanying drawings, whereof Figs. 1 and 2 are vertical sections at right angles one to another, of one constructional arrangement thereof. Fig. 3 is a sectional detail view to a larger scale.

55 As here shown, the retort comprises a

heating zone consisting of a vertical casing or chamber *a* having an upper stationary horizontal wall formed by a tube plate *b* of metal surmounted by a dome or cover *c* having a hopper *d* or inlet for the continuous or intermittent supply of the material, and a gas outlet *e*. Suspended from the tube plate *b* are a plurality of ducts or tubes *f*. These tubes *f* may be flanged to rest upon the tube *b* and may either extend 60 freely through a lower tube plate *g* that is fixed, or be secured to such a tube plate which, as illustrated, is of a floating nature, exemplified as having a skirt *h* which telescopes within a metal casing *i* that surrounds a receiver *m* for spent shale or the like. The lower end of the receiver is provided with an outlet through which the spent material can be discharged in any 65 convenient manner, for which purpose it 70 may be provided with any suitable means, as for instance a bladed wheel *n*, or endless conveyor, adapted for the continuous or intermittent removal of the spent material.

The casing or chamber *a* is provided with an inlet *p* above the lower tube plate *g* and with an outlet *r* below the upper tube plate, for the passage of hot gas coming from a furnace or gas producer *s*, shown as 80 situated at one side of the casing *a*. The gas inlet and outlet and the furnace or gas producer can however be otherwise arranged. Care should be taken to prevent the tubes being heated to too great a degree. 90 The dome or cover *c* and casing or chamber *a* may be provided with suitable cleaning and inspection openings with doors. Also, the tubes *f* may be provided externally with scrapers for keeping them 95 clean, the scrapers being operated by hand or by power, or the tubes may be cleaned periodically by steam or air jets.

Any convenient means may be employed to agitate material whilst it is within the tubes, as for instance spiralokers, of which one is indicated at *t* adapted to be operated, as by a crank *t*¹, one whereof is common to thoseokers that are arranged with their ends in a straight row. Or the material 100 may be forced intermittently or continuously through the tubes *f*. The inlet ends of the tubes may, in some cases, be slightly restricted, as indicated at *f*¹ in Fig. 3, in order 105 that the material within the tubes, may be 110

less liable to choke than would otherwise be the case.

Instead of fixing the tubes to a lower movable tube plate, as hereinbefore described, and as shown in the drawings, so that they can expand downwards, they may be fixed at their lower ends to a stationary tube plate and be fixed to an upper movable tube plate, or be free to move endways through a stationary upper tube plate, so that they can expand upwards. Also, the tubes *f* and their casing or chamber *a*, instead of being arranged vertically as shown, may be arranged horizontally, or be inclined, and means be provided for forcing the material to be treated through the tubes.

What I claim is:—

1. A retort comprising a casing having an inlet for the heating medium at one side and an outlet therefor at the opposite side, a stationary tube plate forming an end wall of the casing, a chamber adjacent said tube plate having an inlet for material to be heated and an outlet for gas or vapour, a plurality of tubes extending from said tube plate substantially throughout said casing and through which material from said chamber passes, a receiver for spent material at the end of the casing opposite to that at which the chamber aforesaid is located, and into which receiver the said tubes discharge, the tubes forming a single group around all of which collectively the heating medium flows, and means whereby spent material can gradually be discharged from the receiver aforesaid, substantially as described.
2. A retort comprising a vertical casing having an inlet for the heating medium at one side and an outlet therefor at the opposite side, a horizontal stationary tube plate at the top of the casing, a chamber surmounting the said tube plate having an inlet for material to be heated and an outlet for gas or vapour, a plurality of tubes suspended from said tube plate and through which material from said chamber passes, a receiver at the bottom of the casing, for reception of spent material, into which the lower ends of the said tubes discharge and an outlet in said receiver for ejecting the spent material, the tubes forming a single group around all of which collectively the heating medium flows, the material to be

treated descending through all the tubes 55 simultaneously and being subjected to substantially the same rapid heating conditions, substantially as described for the purpose set forth.

3. A retort comprising a vertical casing 60 having an inlet for heating medium at one side and an outlet therefor at the opposite side, a horizontal stationary tube plate at the top of the casing, a chamber surmounting the said tube plate and having an inlet 65 for material to be heated and an outlet for gas or vapour, a plurality of tubes suspended from said tube plate and through which material from said chamber passes, a receiver for reception of spent material and 70 into which the lower ends of the said tubes discharge, and means whereby spent material can be gradually discharged from the receiver aforesaid, substantially as described.

4. A retort comprising a vertical casing 75 having an inlet for heating medium at one side and an outlet therefor at the opposite side, a horizontal stationary tube plate at the top of the casing, a chamber surmounting the said tube plate and having an inlet 80 for material to be heated and an outlet for gas or vapour, a plurality of tubes suspended from said tube plate and through which material from said chamber passes, a receiver for reception of spent material 85 from such tubes, and a floating tube plate surmounting said receiver, and in which tube plate the lower ends of the tubes are secured, substantially as described.

5. A retort comprising a vertical casing, 90 a horizontal stationary tube plate at the top thereof, a chamber surmounting the said tube plate, and having an inlet for material to be heated and an outlet for gas or vapour, a plurality of tubes suspended from said tube 95 plate and through which material from said chamber passes, a floating tube plate to which the lower ends of the tubes are secured and having a skirt, a receiver beneath the floating tube plate for reception of spent 100 material, and a casing surmounting the receiver and into which the skirt of the floating tube plate telescopes, substantially as described.

Signed at London, England this third day 105 of July 1924.

WILLIAM GUY-PELL.
